BY
L. B. & G. D. ATTORNEYS

UNITED STATES PATENT OFFICE

JOHN D. ADAMS, OF BRUNSWICK, NEW YORK

COUPON CUTTER

Application filed March 13, 1928. Serial No. 261,397.

My invention relates particularly to coupon cutters of the type consisting merely of an L-shaped element presenting an angular tearing edge along which a coupon may be detached. This type of cutter is ordinarily preferred to the scissors type, due both to the fact that its initial cost is less and to the fact that it is somewhat quicker to use. The only disadvantage of such a device, is that it has a tendency to slip from proper position in use, so that the coupons are not detached along the proper lines, and this is especially the case when an attempt is made to sever the coupons of several bonds piled in register with each other.

According to my invention, a cutter of this preferred type is provided with gripping means, so that when placed in position on a bond, or a number of bonds, the gripping means will engage the paper and hold the cutter in proper position.

Without going further into the general aspects of my invention, I shall proceed to describe it with reference to the accompanying sheet of drawings, wherein

Figure 1 represents in top plan view a preferred embodiment of my invention as applied to an L-shaped cutter.

Figure 2 is a section on line 2—2 of Figure 1.

Figure 3 shows in perspective a modified form of my invention.

Figure 4 shows in perspective a slightly modified form of the device according to Figure 1, and

Figure 5 shows in perspective a further general modification.

Referring now to the drawings, the cutter comprises generally rectangularly disposed arms 10 and 11, presenting sharpened tearing edges 10' and 11'. The cutter is formed of spring metal, and a tongue 12 is struck up from the material of arm 11 behind and longitudinally of tearing edge 11'. Tongue 12 normally overlies the plane of arm 11, as clearly shown in Fig. 2, and a plurality of pins, cusps, teeth, or the like 13 are securely set into tongue 12 to project therebelow at longitudinally spaced points. Further, the

free end of tongue 12 is provided with a knob 14.

In use, the cutter is positioned in the customary manner, whereupon tongue 12 is depressed, thus projecting the points of pins 13 below the lower surface of arm 11, so that they engage the material of the bond or bonds, and the tearing operation can be carried out without any danger of displacement of the cutter.

The embodiment according to Fig. 4 is the same as that of Fig. 1 with the exception that knob 14 is here replaced by equivalent means 15 formed by bending up the material of the tongue at the free end of the latter, and pins 13' are struck out of the material of the tongue.

According to Fig. 3, the cutter consists of arms 16 and 17 from which is struck up a strip composed of angular sections 18 and 19, extending along both of edges 16' and 17'. Sections 18 and 19 are, respectively, provided with downwardly projecting pins 20 and 21 struck from the material of the sections, while a knob-like element 22 is struck up from the material of the strip or tongue at the point of juncture of sections 18 and 19. The obvious advantage of this modified form of cutter, is that the material is gripped behind each section of the tearing edge.

The cutter according to Fig. 5 consists of arms 23 and 24 presenting the tearing edge 23', 24'. Arm 24 has an integral extension which is bent back over the arm to form a tongue 25 in the manner shown. Pins 26 project from the lower surface of tongue 25, and arm 24 is provided with apertures 27 through which pins 26 may project upon depression of tongue 25. Tongue 25 is provided at its free end with a knob 28.

It will be obvious that the described devices may be used in the same manner as the L-shaped cutters of the prior art if pressure is not applied to depress the tongues and project the pins into gripping relation.

While I have described specific embodiments of my invention, it is to be understood that my invention includes all equivalents coming within the terms of the following claims, and that it may be applied to straight

edge instruments other than coupon cutters. In these claims, for convenience in setting out the relation of the parts, I have assumed the device to be in the horizontal position in which it is normally used, and, of course, I do not intend this terminology to be construed restrictively.

I claim:

1. A device of the class described comprising a horizontally extending arm having a tearing edge, a spring tongue integral with said arm and normally lying above the plane defined by the upper surface of said arm, and a pin projecting from said tongue, said pin being projected below the lower surface of said arm upon movement of said tongue toward said arm.

2. A device of the class described comprising a horizontally extending arm having a tearing edge, a spring tongue integral with said arm and normally lying above the plane defined by the upper surface of said arm, and a pin projecting downwardly from said tongue, said arm being apertured behind said tearing edge to permit the projection of said pin below the lower surface of said arm upon movement of said tongue toward said arm.

3. A device of the class described comprising a horizontally extending arm having a tearing edge, a tongue struck up from the material of said arm behind and longitudinally of said tearing edge and a plurality of spaced downwardly projecting pins on the lower surface of said tongue, said pins being projected below the lower surface of said arm upon depression of said tongue.

4. A device of the class described comprising a horizontally extending arm having a tearing edge, a tongue struck up from the material of said arm behind and longitudinally of said tearing edge, a plurality of spaced downwardly projecting pins on the lower surface of said tongue, said pins being projected below the lower surface of said arm upon depression of said tongue, and a knob on the free end of said tongue.

5. A device of the class described comprising a horizontally extending arm having a tearing edge, a tongue struck up from the material of said arm behind and longitudinally of said tearing edge, a plurality of spaced downwardly projecting pins on the lower surface of said tongue, said pins being projected below the lower surface of said arm upon depression of said tongue, and an integrally formed knob on the free portion of said tongue.

6. A device of the class described comprising a plurality of angularly disposed arms lying in a common horizontal plane and presenting an angular tearing edge, a strip comprising angular sections struck up from the material of said arms behind and longitudinally of said tearing edge, and a downwardly projecting pin on each section of said angu-

lar strip, said pins being projected below the lower surface of said arm upon depression of said strip.

7. A device of the class described comprising a plurality of angularly disposed arms lying in a common horizontal plane and presenting an angular tearing edge, a strip comprising angular sections struck up from the material of said arms behind and longitudinally of said tearing edge, a downwardly projecting pin on each section of said angular strip, said pins being projected below the lower surface of said arm upon depression of said strip, and a knob on said strip at the junction of said sections.

8. A device of the class described comprising a plurality of angularly disposed arms lying in a common horizontal plane, and presenting an angular tearing edge, a strip comprising angular sections struck up from the material of said arms behind and longitudinally of said tearing edge, a downwardly projecting pin on each section of said angular strip, said pins being projected below the lower surface of said arm upon depression of said strip, and an integrally formed knob on said strip at the junction of said sections.

9. A device of the class described comprising a horizontally extending arm having a tearing edge, a spring tongue integral with said arm and normally lying above the plane defined by the upper surface of said arm, and a pin struck from the material of the tongue, said pin being projected below the lower surface of said arm upon movement of said tongue toward said arm.

10. A device of the class described, comprising a plate presenting an angular tearing edge, a tongue struck from material of the plate and extending along and behind said tearing edge, the free portion of the tongue lying normally substantially to one side of the plate, a plurality of pins on said tongue spaced longitudinally thereof and projecting toward the plate, said pins being projected beyond the opposite side of the plate upon movement of said tongue toward the latter.

In testimony whereof I have hereunto set my hand.
